UNITED STATES PATENT OFFICE.

HOWARD BROWN, OF SPRINGFIELD, MASSACHUSETTS.

LEDGER-SHEET AND METHOD FOR ITS PRODUCTION.

1,146,997.

Specification of Letters Patent.

Patented July 20, 1915.

Application filed August 1, 1913. Serial No. 782,512.

To all whom it may concern:

Be it known that I, HOWARD BROWN, a citizen of the United States, residing at Springfield, in the county of Hampden and State of Massachusetts, have invented new and useful Improvements in Ledger-Sheets and Methods for Their Production, of which the following is a specification.

It is the object of the present invention to provide paper sheets, suitable for use in loose leaf ledgers and having near the hinged portion of the sheet, an area specially treated to make the sheet more pliant and to permit ready bending when in the ledger without crinkling or puckering at the bend.

In general the product may be said to be a sheet of paper suitable for use in ledgers, but having the area at which the leaf is to be bent, compacted under certain special condition, to bring the fibers close together, but without substantial displacement or fracture, thereby not only reducing the thickness of the sheet at the treated area, but also changing its physical structure and increasing its density and making it more pliant than the body of the sheet and in such a way and under such conditions, that when the leaf is flexed, as it must be in opening the ledger in which it is placed, the leaf will readily bend at the treated area, somewhat as if it were there hinged and without wrinkling or puckering lengthwise of the sheet. The process whereby this result may be obtained, can be applied to ledger papers of standard quality and preferably is applied as a part of the manufacturing operation and before the paper reaches a finished condition on the paper making machine.

In a general way, the process comprises the application to the moving paper or web of paper while in the paper making machine and while under definite and rather exacting physical conditions of a severe compression of the sheet along those areas, which are to serve as the hinges of the ledger pages. The paper sheet under treatment, must be neither too wet nor too dry and the degree of compression and its duration, must be nicely adjusted to the conditions at hand and the subsequent treatment of the sheet must be such as to check the return of the compacted fibers to their initial and loose relation to one another. The apparatus whereby this result may be effect-

ed, may vary in detail, but the process can advantageously be carried out by mounting between the first and second drier drums of a paper making machine, such as a Four-drimer machine, a pair of rolls between which the paper sheet is passed at a rapid rate, one of these rolls bearing hard and inelastic disks which bear with heavy pressure on the sheet of paper, squeezing it against the opposed roll and compacting and densifying the structure where it is compressed. The web thus being treated, passes almost instantly to the second drier drum and the heat treatment at this drum and at the succeeding drums, so fixes or bakes the web structure, that the sheet retains permanently the effect of its severe and momentary compression under the rotating disks.

In the accompanying drawings, Figure 1 is a side elevation of the roller mechanism through which a web of paper may be passed continuously to carry out the process hereinafter claimed. Fig. 2 is an end elevation of the rolls, showing their position adjacent to the first and second drier drums of a paper making machine. Fig. 3 is a perspective view of a ledger sheet treated according to the present process.

The apparatus shown in Fig. 1 comprises a pair of standards 1 and 2 slotted at their upper ends to receive the bearing blocks of the lower roll 3. This roll is of hard inelastic material, preferably metal and is driven in suitable manner, as through a clutch 4 and pinion 5 from a gear 6, which may be one of the gears of the paper making machine. The speed of rotation of roll 3 is such that the sheet of paper 7 passes over the roll at a speed corresponding to the surface speed of the drier drums, with which this device is associated.

The relative locations of the drier drums are indicated in Fig. 2 where drum 8 may be considered as the first drier drum of the series receiving the web of paper as it comes from the press rolls of the machine and delivering it over roll 3 for treatment, after which the paper passes directly to the next drier drum 9 so that the heating and drying action of that drum may serve quickly to fix in the paper, the compressing effect set up at the rolls. The drying drums may be of usual construction with a felt 10 holding the paper web in close contact with the steam heated cylinders of the drier during its rapid movement through this stage of the

machine. The paper may then pass to other drying drums in usual manner and finally through calender rolls, as in ordinary practice. The calendering operation, does not 5 disturb the beneficial effect of compacting the fibers locally and leaves these compacted areas substantially unaffected.

Mounted above roll 3 with its bearing blocks 11, and 12 slidingly positioned in the 10 slotted standards 1 and 2, is a roll or shaft 13, which may be relatively small in diameter and on which a plurality of disks 14 are mounted. These disks are hard and inelastic and may be of brass or of iron or the 15 like, with suitable collars 15 and clamping bolts 16. They preferably are adjustable along the shaft 13 to vary the distance between the treated areas on the paper web. The total length of shaft 13 may vary, but 20 may be long enough for use on an eighty inch paper machine, the disks 14 being sufficient in number and so spaced as to yield paper cutting to advantage commercially. With shaft 13 as long as this, there is a tendency 25 for the shaft to bow up in the middle or to whip under the heavy pressures which must be applied, and to counter-act this tendency and to equalize the pressure throughout the entire width of the sheet, use is made 30 of a weighting roll 17 surmounting the disks 14 and resting directly thereon, with its trunnions housed in bearing blocks 18, slidingly mounted in standards 1 and 2 and held down by stud 19, which passes freely 35 through the cross bar 20, surmounting each standard, but is provided with a hand wheel 21 threaded on the stud in such a way that by turning the wheel, the stud may be raised through the cross members 20 to lift bearing block 18, thereby to lift the weight roll 17 away from the disks 14. Weighted levers 40 22 (Fig. 2) may be provided for each standard to increase the effective pressure of the weight roll 17 on the disk.

45 The disk carrying shaft or roll 13 is rotated at the same peripheral speed as roll 3 by means of a suitable gear 23 and also is capable of longitudinal shifting through the action of a hand wheel 24 mounted to 50 turn a shaft 25, whereon is carried a yoke 26, the arms of which fit in an annular groove 27 cut in the end of shaft 13. It sometimes happens in practice, that the paper strip 17 shifts slowly in its position on roll 3 longitudinally thereof and in order that the compressed areas may be properly located on the sheet, it is desirable to shift the disks, as 55 above recited, to the same degree.

In carrying out the process here disclosed, 60 it is desirable that the material under treatment be brought to proper physical condition before the pressure is applied, as otherwise either the impression will not be retained or there will be destructive crushing 65 and fracture of the fibers. The initial pro-

duction of the paper web may be in accordance with standard practice, as for instance on a Fourdrinier machine and when that continuous strip comes from the press rolls to the first drum of the drier, it is damp and 70 somewhat plastic and the fibers which make up its structure are matted together as a porous mass, substantially uniform in thickness and homogeneous in structure. At the first drier drum, the heat of the drum and 75 the development of water vapor or steam in the web, as the result of that heat, acts to temper the mass of fiber and while removing some of the excess moisture, leaves the structure in pliant condition, best suited for 80 the severe compression which it must undergo at the next stage of its treatment. In this porous and loosely matted condition, with the fibers tempered and plastic, the sheet passes through over roll 3 and under 85 the disks 14 and there for a brief instant is subjected to extreme pressure along predetermined lines, the areas thus compressed having their fibers compacted, but without 90 breaking or destruction and with substantially no displacement of the fibers other than that incident to this compacting. The pressure thus momentarily applied, is extreme, higher than could be applied safely for prolonged periods and after this momentary compression, the paper goes almost instantly to the second drier drum and then on around succeeding drums, the action of these drums serving to fix or bake in the effect produced by the disks, stiffening up 95 the fiber structure and rendering the sheet firm and hard for delivery to the calender rolls. It thus results that areas which have undergone extreme compression and quick baking, are still in the paper when it reaches the calenders and are not disturbed 100 in the calender rolls, but remain characteristic features of the sheet. Ultimately the long web of paper with its longitudinally extending treated areas may be cut up 110 into ledger sheets of the general character shown in Fig. 3 with the treated areas extending across to constitute the hinge or bending portion of the sheet. This hinge or condensed portion of the sheet gives the 115 paper more flexibility and the book made up of these sheets when open, will lie flat and in convenient position for use.

I claim:

1. Ledger paper for use in loose leaf books 120 having areas in the form of straight lines or bands therein at which the fiber structure is more dense and at which the sheet has been rendered more flexible by extreme and momentary compression of the fiber structure while in a damp and plastic condition.
2. The method of producing paper suitable for use in loose leaf ledgers and having therein areas of greater flexibility than the main body of the sheet, which consists in 130

compressing the fiber structure of the sheet after it has been completely formed and when but partially dry, these compressions being along predetermined straight lines and 5 their effect being fixed in the paper sheet by rapid drying of the paper web after the compression has taken place.

3. The method of producing paper having therein areas of greater flexibility than 10 the main body of the sheet which consists in treating the paper while passing through the paper making machine and while in the damp and plastic condition which is to be found between the first and second drier 15 drums, the treatment consisting in subjecting the sheet along predetermined areas to extreme and momentary compression, whereby the fiber structure is compacted locally and thereafter quickly subjecting the sheet 20 with its compressed areas to a drying operation whereby the effect of the compression is fixed in the fiber structure to produce areas of high density and of greater flexibility than in the main body of the sheet.

25 4. The method of treating paper to render it better adapted for use in loose leaf books, which consists in subjecting the paper as it comes from the first drier drum of the paper making machine to the compressing action 20 of rigid disks contacting directly with the moving paper web and squeezing it tightly against an opposed roll and then quickly

drying the material so treated to fix therein the effect of this momentary and extreme compression so that the final product may 35 have areas of greater density and greater flexibility than the main body of the sheet.

5. The process of making ledger paper, which consists in treating the paper as it goes through the paper making machine by 40 subjecting the paper web while in a damp and plastic condition to extreme and momentary compression along limited areas of the web to thereby densify the fiber structure at these areas and thereafter drying the sheet 45 to fix in the paper the effect of this compression and to yield a firm product suitable for use in loose leaf books with the compressed areas positioned to give flexibility to the 50 pages of the book.

6. Ledger paper adapted to be used for loose leaf ledger sheets, having a band or stripe therein, wherein the paper is compacted so as to make it more flexible but not substantially weaker along said band or 55 stripe.

In witness whereof, I hereunto subscribe my name to this specification in the presence of two witnesses.

HOWARD BROWN.
